[57] CLAIM

The ornamental design for broadhead arrow puller, as shown and described.

DESCRIPTION

FIG. 1 is a right side elevational view of a broadhead arrow puller showing my new design, the left side being a mirror image thereof;

FIG. 2 is a top plan view thereof with a stud cap removed, the bottom plan being a mirror image thereof;

FIG. 3 is a front view thereof; and,

FIG. 4 is a front view of FIG. 1.

The broken line showing of a broadhead arrow is for illustrative purposes only and forms no part of the claimed design.
